Attorney.*

UNITED STATES PATENT OFFICE.

LEO SHLICK, OF BOSTON, MASSACHUSETTS.

BEATING ENGINE.

Original application filed February 17, 1921, Serial No 445,736. Divided and this application filed February 1, 1927. Serial No. 165,251.

This invention relates to certain improvements in machines for the production of pulp in the manufacture of paper, the same being divided out from my application for 5 patent filed February 17, 1921, Serial No. 445,736 which has become Patent 1,623,364.

In the drawings forming part of this specification, Fig. 1 is a side view of a beating engine embodying my improvements. 10 Fig. 2 is a side sectional view of the same. Fig. 3 is a plan view on a smaller scale. Fig. 4 is a sectional detail view of the lifting wheel for dipping up the stock from in front of the beater roll and delivering it back of 15 the back-fall.

As illustrated in Fig. 3, the tub 1 has a midfeather 2 and a beater roll 3 in its channel 4, and a bed-plate 5 beneath the beater roll. In the channel 4 is located a lifting 20 wheel 6 provided with a plurality of radially disposed partitions 7, and an axially disposed cylinder 9 apertured at 10 within the wheel, but prolonged beyond the edge of the tub to discharge its contents into a 25 basin 11 from which a pipe 12 passes along the outside of the tub and thence in through the side of the latter to a mouth 13 in the face of the back-fall 14.

This lifting wheel is rotated by the flow 30 of the stock toward the beater roll 3, and is thereby made to elevate a portion of the stock, discharge it into the basin and then deliver it to the back-fall. The lifting wheel being covered at its ends with a fine screen 35 15, only the more fluid of the stock is delivered to the back-fall. This aids in accelerating the flow of the pulp down and away from the back-fall, by its introduction of a more fluid portion beneath the heavier 40 stock; and it also aids in preventing precipitation of stock at the ends of the mid-feather.

The hood 16 is pivotally supported at 17, and its free edge 19 is retained in position 45 by means of arms 20 whose extremities 21 rest upon the bearing boxes 22 of the beater roll axle 23. Hence, whenever the beater roll jumps because of any sudden accumulation of lumps between it and the bed-plate, 50 the edge or lip 19 rises also; and it can consequently remain close to the roll without danger of being struck by the fly-bars of the latter. The hood being pivotally supported at 17 above the back of the backfall,

its weight is made sufficient to retain its edge 55 19 close to the upper portion of the periphery of the roll during all normal conditions of the stock, but when abnormally large and tough lumps of stock come between the doctor 19 and the roll, which might cause injury to the parts were the hood bound to the roll for its downward as well as its upward play, the hood can rise and permit the lumps to pass. As shown in Fig. 3, these 60 fly-bars 24 are bent at their midlengths in 65 a manner to present the apex of each to the bed-plate, and thereby act to facilitate the expulsion of the entrained air from between them, and to permit the stock to enter more freely between the fly-bars and bed-plate, 70 and to be more perfectly acted upon thereby.

The hood 16 is given a curved arch, and the back-fall is provided with an adjustable plate 25 whose upper portion is curved to a limited extent concentric with the arched 75 hood, in order that as the stock is shot upward from the beater roll, it will pass freely along the curved under surface of the arch and thence on in a direction parallel with the face of the back-fall and into the channel with an increased velocity. I have found that by having the hood 16 present an edge close to the beater roll so that the stock 80 passing down from the back-fall, at an approximate parallel thereto, it will materially 85 speed up the flow of stock. In beating engines which I have built thus constructed, I have been able to practically double the 90 speed of the stock-flow without having increased the power required for rotating the 95 roll.

A portion of the stock will go past the lip 19 of the hood. To receive this, a second hood 26 is located above the beater roll, having an intermediate floor 29 and a discharge mouth 30, whereby the more fluid portion of the stock which passes over the beater roll will fly off from the latter at a tangent as it passes the topmost part of the roll, and will be caught upon the floor 100 29 and delivered to the mouth 30; the quantity thereof being varied by means of an 105 adjusting gate 31 movable toward and from

the floor 29. Some of the stock still clinging to the beater roll will fly therefrom at a tangent below the floor 29 and will be likewise delivered to the mouth 30; this latter amount being in its turn varied by adjusting the gate 32. That of the stock still clinging to the fly-bars will be finally delivered to the bed-plate again and further macerated and intermixed with the stock approaching the beater roll.

The fluid stock thus delivered to the mouth 30 is to be removed as already sufficiently treated.

I prefer to provide one or both ends of the midfeather 2 with adjustable rounded heads 33 adapted to be varied in distance from the neighboring ends of the tub. This adjustment is performed by means of tongues 34 slidably fitting the grooves 35 in the ends of the midfeather, and held at desired points by bolts 36. By thus narrowing the spaces between the heads 33 and the ends of the tub, the danger of the stock's settling thereat and obstructing the flow is reduced to a minimum.

When all the stock in the tub 1 has been sufficiently treated, the vertically slidable gate 37 at an end of the tub is slowly lowered to permit the stock to be discharged, a screw rod 39 controlling the movement of the gate. The gate should not, however, be lowered clear to the floor of the tub, but should stop with its top edge far enough above the floor to hold back all particles of metal, and any hard lumps of pulp which had failed to be ground up. To aid in this discharge, the gated end of the tub is supported upon one or more screw rods 40 and a hand wheel-nut 41 resting upon a standard 42, while the opposite end of the tub is supported upon pivotal legs 43. Consequently, as the level of the discharging stock lowers, the hand wheel 41 can be turned to depress the gated end of the tub and thereby to assist in the drainage.

As shown in Fig. 2, the back-fall 14 rises to a height above the level of the topmost periphery of the beater roll 3, whereby the stock shot up and over the crest of the back-fall is given an impetus in its descent which greatly increases its speed of flow along the channels of the tub. Moreover, the hood 16 and the upper portion of the back-fall plate 25 are given concentric curves, whereby to cause the stock to shoot up and over the back-fall and to follow the curve of the hood and to thereby prevent the accumulation of lumps of stock, which is otherwise liable to occur by the repeated drying thereon of small amounts of the liquid stock until they have accreted into marked obstructions to the flow.

What I claim as my invention is:

1. A beating engine comprising a beater roll, bed-plate, back-fall, and means for sep-

arating part of the stock from that approaching the beater roll, and delivering it beyond the back-fall.

2. A beating engine comprising a beater roll, bed-plate, back-fall, and means for separating part of the stock from that approaching the beater roll, and delivering it upon the back surface of the back-fall.

3. A beating engine comprising a beater roll, a bed-plate, a back-fall having a cavity opening to its back surface, and means for separating part of the stock from that approaching the beater roll, and delivering it into said cavity.

4. A beating engine comprising a beater roll, a bed-plate, a back-fall and means for separating part of the stock from that approaching said beater roll and delivering it beyond the back-fall, said means embracing a tubular conduit opening through to the back face of the back-fall and having a laterally extended mouth thereat.

5. A beating engine as set forth in claim 4 wherein the laterally extended mouth is provided with a lip close above it.

6. A beating engine comprising a beater roll, a bed-plate, a back-fall, and means for separating stock from that approaching the beater roll embracing a revolving wheel turned by the flow of the stock.

7. A beating engine as set forth in claim 6 the revolving wheel whereof comprises a hollow axle, vanes and a strainer over an end of the wheel.

8. A beating engine as set forth in claim 6, the revolving wheel whereof comprises a cylindrical shell, radially disposed vanes, and a tubular axle apertured between the vanes and projecting at one end beyond the said shell.

9. A beating engine comprising an elongated tub, a midfeather therein, and a beater roll in one of the channels, an end of the midfeather having a rounded head adjustable relative to the adjacent end of the tub.

10. A beating engine comprising an elongated tub, a midfeather therein, a beater roll and a bed-plate in one of the channels, each end of the midfeather being provided with a rounded head adjustable relative to the adjacent end of the tub.

11. A beating engine comprising an elongated tub having a beater roll therein, the tub having an opening through its wall, and a vertically slidable gate therefor provided with means for lowering it to permit the escape over its top edge of the tub's contents.

12. A beating engine comprising an elongated tub having beating mechanism therein, and an opening through an end wall, a vertically slidable gate for said opening, vertically adjustable support for the gated end of the tub, and pivotal support for its other end.

13. A beating engine as set forth in claim 130

- 11, the vertically slideable gate of which is provided with adjusting means embracing a screw rod and a hand wheel nut.
14. A beating engine comprising a tub, a beater roll, a back-fall, and a hood located above the back-fall and pivotally supported at its rear edge, its weight being supported by the beater roll. 45
15. A beating engine comprising a tub, a beater roll having a shaft and vertically movable boxes for the latter, an arched roof pivotally supported at its rear edge and having its free edge close to the periphery of said roll, and arms rigid with said hood and resting upon said boxes. 50
16. A beating engine comprising a tub, a beater roll, and a stationary hood above said roll provided with a discharge mouth and an intermediate floor and adjustable gates. 55
- 20 17. A beating engine comprising a beater roll, a back-fall, and a hood located above the latter, and having one edge almost contacting with and tangential to said roll, and curved substantially concentric with the upper portion of the back-fall, the back-fall being provided with a slidably adjustable plate for constricting the passage of stock to the back-fall. 60
- 30 18. A beating engine comprising a beater roll, a back-fall having its crest above the topmost point of said roll, and a hood concentric with the upper portion of said crest and having its edge adjacent said roll at the level approximately half way between that of the said crest and the axis of said roll. 65
- 35 19. A beating engine comprising a tub, a midfeather, beater mechanism in one of the channels of the tub, and means for adjustably expanding and contracting the stock passages at the ends of the midfeather. 70
- 40 20. A beating engine having a beater roll, a backfall, and a member provided with an edge close to the upper periphery of said roll, and performing the function of a doctor, said member being pivotally supported to permit said edge to be swung toward and from said periphery, means connected with the beater roll whereby the upward movements thereof communicate upward movements to said edge, and gravitationally actuated means for lowering said edge and for preventing its being forced upward by the action of hard lumps of stock coming between said edge and the periphery of the roll. 75
21. A beating engine having a beater roll, a back-fall rising higher than the axis of said roll, vertically movable trunnions carrying said roll, and a hood pivotally supported at a point above the back of said backfall and having an edge close above the periphery of said roll and supported thereat by means of said trunnions, said edge performing the function of a doctor, and said hood being heavy enough to hold said edge from yielding to the impact of hard lumps of the stock. 80
22. A beating engine comprising a tub, a beater roll, a back-fall located back of the roll, and a curved hood located above the back-fall, the curvature of which hood approximates that of the beater roll, one edge of the hood being close to the roll and its curvature being made to direct the stock which meets it, obliquely downward at an angle nearly parallel to the stock flowing from the back-fall. 85

In testimony that I claim the foregoing invention, I have hereunto set my hand this 18th day of January, 1927.

LEO SHLICK.
